UNITED STATES PATENT OFFICE.

CHARLES B. WHITTELSEY, OF HARTFORD, CONNECTICUT, ASSIGNOR TO UNITED STATES
TIRE COMPANY, A CORPORATION OF NEW YORK.

DESIGN FOR A TIRE.

52,975.

Specification for Design.

Patented Feb. 4, 1919.

Application filed December 7, 1914. Serial No. 875,990. Term of patent 14 years.

To all whom it may concern:

Be it known that I, CHARLES B. WHITTELSEY, a citizen of the United States, residing at Hartford, in the county of Hartford and State of Connecticut, have invented a new, original, and ornamental Design for Tires, of which the following is a specification, reference being had to the accompanying drawing, in which—

Figure 1 is a plan view; and

Fig. 2 is an elevation of a part of a tire showing my new design.

I claim:

The ornamental design for a tire, as shown.

CHARLES B. WHITTELSEY.

Witnesses:

WM. J. PLATT,
JULIA E. BRENNAN.
